CUFF FASTENER

Martin J. Ellsasser, Syracuse, N. Y.

Application July 6, 1938, Serial No. 217,736

3 Claims. (Cl. 24—102)

This invention relates to fasteners for cuffs and for analogous situations, particularly for so-called French or starched cuffs, such as are used by clergymen, funeral directors, and others on formal occasions, and has for its object a particularly simple and economical-to-manufacture cuff fastener which does not come apart and permits a comparatively wide opening of the cuff without detaching the fastener from the cuff, and which is readily restored to normal position by merely pinching together the button heads of the fastener.

More specifically, it has for its object a fastener of this type consisting of a main link which normally extends lengthwise between the opposite flaps or sides of the cuff, additional links pivoted to opposite ends of the main link, and normally overlying the main link with their free ends adjacent each other, and buttons having shanks pivoted to the free ends of the additional links, together with means having a snap action for holding the additional links in their normal position overlying the main link, when the cuff is closed, the links being unlocked by merely pressing the buttons together, and when the links are unlocked, and the margins of the cuff separated, the main link swings into a transverse position between the margins of the cuff, and at the same time, the additional links swing in opposite directions into a position in which they are nearly lineal extensions of the main link, and the shanks of the buttons extend into lineal extensions of the additional links, thus affording a wide opening of the cuff.

The invention consists in the novel features and in the combinations and constructions hereinafter set forth and claimed.

In describing this invention, reference is had to the accompanying drawing, in which like characters designate corresponding parts in all the views.

Figure 1 is a side elevation on an enlarged scale of this fastener applied to a cuff, the contiguous portion of which is shown in section.

Figure 2 is a plan view on an enlarged scale of the fastener showing the parts in their normal position.

Figure 3 is a plan view showing the parts in their extended position.

Figures 4 and 5 are sectional views on lines 4—4 and 5—5, Figure 2.

1 designates the main link; 2 and 3 the additional links pivoted at 4 and 5 respectively to opposite ends of the main link 1. 6 and 7 designate respectively the buttons which button

through the button-holes of opposite flaps of the cuff C, the buttons having shanks 8 and 9 respectively pivoted at 10 and 11 to the outer ends of the additional links 2 and 3. The links 2 and 3 are foldable in opposite directions about their pivots 4, 5 from normal position in which they overlie the link 1 into extended position and vice-versa, and one link, as the link 3, has an extension 3^a at its end remote from its pivot 5 which passes over and drops behind a corresponding extension 2^a on the link and interlocks therewith when the links 2, 3 are in normal position overlying the main link, and is formed of resilient material to press its extension 3^a flatwise toward the extension 2^a of the link 2 and the main link. The extensions 2^a, 3^a are formed by cut-outs 12 in the ends of the links 2, 3. The extensions constitute snap-catch means. The advance edges of the extensions 2^a, 3^a, with respect to the movement of the links 2, 3 into their normal position are beveled at 13 to facilitate ratcheting of the extension 3^a over the extension 2^a into a position where it locks behind the extension 2^a. The link 1 is provided with stop shoulders 14 and 15 for limiting the collapsing movement of the links 2, 3 respectively on the main link, the stop shoulder 15 being so arranged as to limit the movement of the link 3 after it has slightly over-run its normal position in interlocking engagement with the pivot 10 between the shank 8 of the button 6 and the link 2, so that there is a clearance at 15^a to permit the unlatching when the buttons are pinched toward each other. Also, suitable stop shoulders 16 and 17 are provided for limiting the outward extending movement of the links 2, 3 before the links enter a dead center line L passing lengthwise of the main link 1 through the pivot points, 4, 5.

The shank 8 of the button 6 for the link 2 is formed with a cam surface 8^a up which the end of the link 3 rides when the buttons are pinched toward each other, this raising the extension 3^a up from behind the extension 2^a and out of interlocking engagement therewith as shown in Figure 5. The clearance 15^a permits this unlocking movement. When the parts are in the position illustrated in Figure 5, the link 3 is pressed against the stop shoulder 15 and is under tension and when the parts are quickly pulled apart, the tension is overcome and the extension 3^a is moved beyond its interlocking position with the extension 2^a and allows the links to open.

In operation, the buttons are first applied to

- the button-holes of the cuff with the fastener in extended position, and then by pinching the buttons toward each other, the main link will move from a transverse position relative to the cuff into a lengthwise position and at the same time, the additional links 2, 3 will fold inwardly in opposite directions to overlie the main link 1, and the extension 3^a of the link 3 snap into engagement behind the extension 2^a of the link 2, due to the tensioning of the link 3 and the camming action of the extensions 2^a and 3^a of the links 2 and 3. To unfasten the fastener and open the cuff, without detaching the fastener, the button heads 6, 7 are pressed together slightly, disengaging the interlocked extensions due to the extension 3^a riding up the cam 8^a, and then quickly pulled apart, this unlocking the snap-catch and permitting the cuff to be opened and the fastener to move into extended position.

What I claim is:

1. A cuff fastener comprising a main link, additional links pivoted to opposite ends of the main link and normally overlying the main link and foldable into a position in which they form extensions of the main link, buttons having shanks pivoted to the outer ends respectively of the additional links, and said outer ends interlocking to provide snap-catch means for holding the additional links in their normal position overlying the main link, means for limiting the relative pivotal movement of the main and additional links in either direction including stops on the additional links coacting with the main link for limiting the outward movement of the additional links before the additional links enter a dead center line passing through the pivots connecting the additional links to the opposite ends of the main link.
2. A cuff fastener comprising a main link, additional links pivoted to opposite ends of the main link and normally overlying the main link,

the end of one additional link overlapping the end of the other, said ends coacting when in a normal position and providing means for interlocking therewith with a snap action, the additional links being movable on their pivots outwardly in opposite directions into position in which they are extensions of the main link, stops on the main link and coacting with the additional links for limiting the pivotal movement of the additional links, when the same are in their normal position, buttons having shanks pivoted to the ends of the additional links, stops on the additional links coacting with the main link for limiting the said pivotal movement of the additional links before the additional links come into a dead center line passing lengthwise of the main link and through the pivots connecting the additional links and the main link.

3. A cuff fastener comprising a main link, additional links pivoted to opposite ends of the main link and normally overlying the main link, the end of one additional link overlapping the end of the other, said ends coacting when in a normal position and providing means for interlocking therewith, with a snap action, the additional links being movable on their pivots outwardly in opposite directions into position in which they are extensions of the main link, stops on the main link and coacting with the additional links for limiting the pivotal movement of the additional links, when the same are in their normal position, buttons having shanks pivoted to the ends of the additional links, stops on the additional links coacting with the main link for limiting the said pivotal movement of the additional links before the additional links come into a dead center line passing lengthwise of the main link and through the pivots connecting the additional links and the main link which overlaps the other additional link being of resilient material tensioned to press toward the main link.
